UNITED STATES PATENT OFFICE.

FOUSHEE J. TEBBS, OF CYNTHIANA, KENTUCKY.

LIFTING DEVICE.

Application filed May 17, 1922. Serial No. 561,639.

To all whom it may concern:

Be it known that I, FOUSHEE J. TEBBS, a citizen of the United States, residing at Cynthiana, in the county of Harrison and State of Kentucky, have invented certain new and useful Improvements in Lifting Devices, of which the following is a specification.

This invention relates to lifting devices and is intended more particularly for use in transferring an invalid from a bed to a chair or from one bed to another bed or from a chair to a bed. The invention seeks to provide a device which may be easily operated and will firmly support the patient while he is being transferred from a bed or a chair to another resting place. The invention is illustrated in the accompanying drawings and will be hereinafter fully set forth.

20 In the drawings—

Figure 1 is a perspective view of my improved lifting device;

Fig. 2 is an enlarged transverse section on the line 2—2 of Fig. 1.

25 In carrying out my invention, I employ a stand comprising a base 1 and legs 2 supporting the same, the upper end of each leg being fitted in a recess 3 in the edge of the base and held therein by a pin or bolt 4. The legs 30 are each constructed at its upper end with a tongue 5 fitting against the base of the respective recess 3 so that spreading of the legs, when the device is in use, will be prevented. At the same time, the bolts or pins 4 are 35 readily removable so that the device may be stored away in a small compass when it is not in use. A king bolt 6 is fitted vertically through the center of the base 1, and secured upon the upper side of the base concentric with the king bolt is a supporting 40 plate or disk 7 having an annular flange 8 at its edge to co-operate with and support a turning plate 9 secured to the under side of a head or fulcrum block 10. The turning 45 plate 9 is provided with a depending flange 11 which fits within the flange 8 so as to maintain the concentric relation of the members 7 and 9 and at the center of the turning plate 9 is a depending hub 12 fitting loosely 50 about the king bolt and also fitting loosely within the central opening 13 in the supporting plate 7. The plate 9, moreover, rests upon the edge of the flange 8 so that it will be firmly supported but may be freely rotated. The head or fulcrum block 10 receives the upper end of the king bolt which

is seated in the base of a slot or notch 14 in the head, as clearly shown in Fig. 2. A lever 15 is pivotally supported within the slot 14 by a pin or bolt 16 inserted through the head 10 and through the lever, as clearly shown. One end of this lever is free so as to receive power and at the other end of the lever is a suspension hook 17. A sling is employed consisting of straps 18 secured at their ends to rings 19 and connected intermediate their ends by bracing straps 20. These straps may be of leather or any other sufficiently flexible and strong material and should be of proper dimensions to comfortably support the patient when passed beneath his body. A strap 21 is doubled upon itself through the rings 19 and is inserted through a ring 22 which is adapted to be engaged upon the suspension hook 17, the ends of the strap being fastened by a buckle or equivalent device 23.

In the use of the device, the sling is passed under the patient and the strap 21 is then engaged through the several rings and fastened, as will be readily understood. By applying power to the free end of the lever 15, the sling with the patient therein will be raised from the bed and when the patient is clear of the bed the lever may be moved laterally so that it and the head 10 will turn pivotally about the king bolt 6 and bring the patient into proper position to be lowered onto another bed or into a chair or other support. The device may be readily set up for use and is light so that it may be easily moved from point to point as its use is needed.

Having thus described the invention, what is claimed as new is:

1. A lifting device comprising a stand, a circular disc secured on the upper side of the stand and provided with an annular upstanding flange and having a central opening therethrough, a turning plate supported on said annular flange, a depending flange on the said turning plate engaging within said annular flange, a hub on said turning plate engaging in said opening, a head attached to said turning plate and having spaced jaws extending upwardly from said head, a pivot pin carried by said jaws, a securing element connecting said head to said stand, a lever supported on said pivot pin between said jaws, and load-engaging means attached to one end of said lever. 110

2. A lifting device comprising a stand,

a circular disc secured on the upper side of the stand and provided with an annular upstanding flange and having a central opening therethrough, a turning plate supported on said annular flange, a depending flange on the said turning plate engaging within said annular flange, a hub on said turning plate engaging in said opening, a head attached to said turning plate and having spaced jaws extending upwardly from said head, a pivot pin carried by said jaws, a securing element connecting said head

to said stand, a lever supported on said pivot pin between said jaws, load-engaging means attached to one end of said lever, said stand including a base provided with perpendicular recesses at its edge, legs having tongues fitting tightly in said recesses and contacting with the three sides thereof, and pins holding said tongues in said recesses. 15 20

In testimony whereof I affix my signature.

FOUSHEE J. TEBBS. [L. S.]
